FINGER RING

Daniel Shiman, Maplewood, N.J., assignor to Shiman Manufacturing Company, Inc., Newark, N.J., a corporation of New York

Filed Dec. 23, 1968, Ser. No. 15,090

Term of patent 14 years

Int. Cl. D11—01

U.S. Cl. D45—10

FIG. 1.

FIG. 2.

FIG. 3.

FIG. 1 is a perspective view of a finger ring showing my new design;

FIG. 2 is a side elevation thereof showing the side opposite to that seen in FIG. 1; and

FIG. 3 is a top plan view thereof.

I claim:

The ornamental design for a finger ring, as shown.
